(57) CLAIM

The ornamental design for an elevated dog bowl with handle, as shown and described.

DESCRIPTION

FIG. 1 is a top rear perspective view of an elevated dog bowl with handle showing my new design;

FIG. 2 is a sectional view thereof, taken along line 2—2 of FIG. 6;

FIG. 3 is a sectional view thereof, taken along line 3—3 of FIG. 6;

FIG. 4 is a front elevational view thereof;

FIG. 5 is a rear elevational view thereof;

FIG. 6 is a left side elevational view thereof, the right side being a mirror image;

FIG. 7 is a top plan view thereof;

FIG. 8 is a top rear perspective view of a second embodiment of an elevated dog bowl with handle showing my new design;

FIG. 9 is a sectional view thereof, taken along 9—9 of FIG. 11;

FIG. 10 is a rear elevational view thereof;

FIG. 11 is a left side elevational view thereof, the right side being a mirror image;

FIG. 12 is a top plan view thereof;

FIG. 13 is a top rear perspective view of a third embodiment of an elevated dog bowl with handle showing my new design;

FIG. 14 is a sectional view thereof, taken along line 14—14 of FIG. 16;

FIG. 15 is a front elevational view thereof;

FIG. 16 is a right side elevational view thereof;

FIG. 17 is a top plan view thereof;

FIG. 18 is a sectional view of a fourth embodiment of an elevated dog bowl with handle showing my new design, taken along line 2—2 of FIG. 6. The only difference between this embodiment and embodiment 1 is that the bottom is not claimed;

FIG. 19 is a sectional view thereof, taken along line 3—3 of FIG. 6;

FIG. 20 is a sectional view of a fifth embodiment of an elevated dog bowl with handle showing my new design, taken along line 9—9 of FIG. 11. The only difference between this embodiment and embodiment 2 is that the bottom is not claimed; and,

FIG. 21 is a sectional view of a sixth embodiment of an elevated dog bowl with handle showing my new design, taken along line 14—14 of FIG. 16. The only difference between this embodiment and embodiment 3 is that the bottom is not claimed.

The broken lines shown in FIGS. 18-21 are for illustrative purposes only and form no part of the claimed design.
